[57] **CLAIM**

The ornamental design for a cart, as shown and described.

DESCRIPTION

FIG. 1 is a perspective view of a cart showing my new design;

FIG. 2 is a top plan view thereof;

FIG. 3 is a side elevational view thereof, the opposite side being a mirror image of that shown;

FIG. 4 is a front elevational view thereof;

FIG. 5 is a rear elevational view thereof; and

FIG. 6 is a perspective view from underneath of the top horizontal shelf of the cart shown separately for ease of illustration.

FIG. 1

FIG. 2

FIG. 3

FIG. 4

FIG. 5

FIG. 6
